US00D957934S

(12) **United States Design Patent** (10) Patent No.: **US D957,934 S**
Smith et al. (45) Date of Patent: ** *Jul. 19, 2022

(54) **CONTAINER**(71) Applicant: **All Plastic, Inc.**, Gold River, CA (US)(72) Inventors: **William Thomas Smith**, Fair Oaks, CA (US); **Cheryl Ann Smith**, Fair Oaks, CA (US)(73) Assignee: **ALL PLASTIC, INC.**, Rancho Cordova, CA (US)

(*) Notice: This patent is subject to a terminal disclaimer.

(**) Term: **15 Years**(21) Appl. No.: **29/782,447**(22) Filed: **May 6, 2021****Related U.S. Application Data**

(60) Division of application No. 29/763,822, filed on Dec. 24, 2020, now Pat. No. Des. 922,198, which is a division of application No. 29/733,779, filed on May 6, 2020, now Pat. No. Des. 908,484, which is a division of application No. 29/665,425, filed on Oct. 3, 2018, now Pat. No. Des. 887,843, which is a continuation-in-part of application No. 29/663,940, filed on Sep. 20, 2018, now Pat. No. Des. 902,028, which is a continuation-in-part of application No. 29/663,942, filed on Sep. 20, 2018, now Pat. No. Des. 904,185, which is a continuation-in-part of application No. 29/659,740, filed on Aug. 10, 2018, now Pat. No. Des. 902,718.

(57) **CLAIM**

We claim the ornamental design for a container, as shown and described.

DESCRIPTION

FIG. 1 is a perspective view of a container in accordance with a first variant of said Design, in which the plug is in a closed position;

FIG. 2 is a top plan view of the container shown in FIG. 1; FIG. 3 is a bottom plan view of the container shown in FIG. 1;

FIG. 4 is a rear view of the container shown in FIG. 1; FIG. 5 is a right side view of the container shown in FIG. 1; FIG. 6 is a front view of the container shown in FIG. 1; FIG. 7 is a left side view of the container shown in FIG. 1; FIG. 8 is a perspective view of a container shown in FIG. 1, in which the plug is in an open position;

FIG. 9 is a top plan view of the container shown in FIG. 8; FIG. 10 is a bottom plan view of the container shown in FIG. 8;

FIG. 11 is a rear view of the container shown in FIG. 8; FIG. 12 is a right side view of the container shown in FIG. 8;

FIG. 13 is a front view of the container shown in FIG. 8;

FIG. 14 is a left side view of the container shown in FIG. 8; FIG. 15 is a perspective view of a container in accordance with a second variant of said Design, in which the plug is in a close position;

FIG. 16 is a top plan view of the container shown in FIG. 15; FIG. 17 is a bottom plan view of the container shown in FIG. 15;

FIG. 18 is a rear view of the container shown in FIG. 15; FIG. 19 is a right side view of the container shown in FIG. 15;

FIG. 20 is a front view of the container shown in FIG. 15; FIG. 21 is a left side view of the container shown in FIG. 15; FIG. 22 is a perspective view of a container shown in FIG. 15, in which the plug is in an open position;

FIG. 23 is a top plan view of the container shown in FIG. 22; FIG. 24 is a bottom plan view of the container shown in FIG. 22;

FIG. 25 is a rear view of the container shown in FIG. 22; FIG. 26 is a right side view of the container shown in FIG. 22;

FIG. 27 is a front view of the container shown in FIG. 22; and,

FIG. 28 is a left side view of the container shown in FIG. 22. The broken lines depict portions of the article that form no part of the claimed design.
